UNITED STATES PATENT OFFICE.

HARRY P. DAVIS, OF PITTSBURG, AND GILBERT WRIGHT, OF WILKINSBURG, PENNSYLVANIA, ASSIGNORS TO THE WESTINGHOUSE ELECTRIC AND MANUFACTURING COMPANY, OF PENNSYLVANIA.

HIGH-TENSION-CIRCUIT BREAKER.

SPECIFICATION forming part of Letters Patent No. 629,664, dated July 25, 1899.

Application filed March 23, 1899. Serial No. 710,216. (No model.)

To all whom it may concern:

Be it known that we, HARRY P. DAVIS, residing at Pittsburg, and GILBERT WRIGHT, residing at Wilkinsburg, in the county of Allegheny and State of Pennsylvania, citizens of the United States, have invented a new and useful Improvement in High-Tension-Circuit Breakers, (Case No. 811,) of which the following is a specification.

10 Our invention relates to automatic devices employed for interrupting electric circuits upon the passage therethrough of currents that are in excess of the predetermined quantity for which the device is adjusted.

15 The object of our invention is to provide a circuit-breaker which shall be simple in construction and effective in operation and which shall be especially adapted for high-voltage circuits—such, for example, as those 20 employed for transmitting energy over long distances for power or lighting purposes.

In the accompanying drawings, Figure 1 is a side elevation of a circuit-breaker constructed in accordance with our invention, 25 parts being broken away and others shown in section. Fig. 2 is a plan view of the circuit-breaker, looking upward, parts being broken away in order to more clearly illustrate the operation and relative relation of certain 30 other parts.

The circuit-breaker constituting the subject-matter of our present invention is intended for high-tension circuits, and the base-plate 1 will usually be a switchboard-panel of 35 marble, slate, or other suitable non-conducting material. One of the stationary terminals of the main circuit is a block 2, clamped or otherwise fastened to one end of a supporting-arm 3 and provided with a contact-piece 4, that is built up of laminæ. This terminal is also provided, above the laminated contact-piece 4, with a block 5, of carbon or other 40 substantially infusible conducting material. The contact-terminals 6 and 7, respectively 45 coöperating with those above described, are mounted upon the upper end of a non-conducting arm 8, which may be of any desired length, depending upon the electromotive force to be interrupted. A very high elec- 50 tromotive force obviously requires a long arm

in order that the movable terminals may be separated a maximum distance from the stationary terminals to break the arcs that form when the separation takes place. A flexible cable 9 projects through the base-board or 55 panel for circuit connection and upward through the arm 8, which is hollow and is connected to a metal head 8^a, which is provided with the main movable terminal plate 6 and the carbon block 7, which constitutes 60 the movable shunt-terminal. It will thus be seen that the main circuit and the shunt-circuit are each interrupted at a single point, thus permitting of such a wide separation of the circuit-terminals as will insure the breaking 65 of the arc no matter what the electromotive force may be.

For supporting the movable members of the circuit-breaker we provide two brackets 10, between the outer ends of which is a rod 11, on which is loosely mounted a frame 12, having triangular-shaped ends 12^a, projecting outwardly, and a middle piece 12^b, projecting inwardly. The lower end of the arm 8 is clamped in a socket 13, and the latter is loosely mounted upon a rod 14, which connects the outer corners of the triangular ends 12^a of frame 12. Another rod 15 connects the lower corners of the triangular pieces 12^a, and to this are loosely connected the outer 75 ends of two lever-arms 16. The inner ends of the lever-arms 16 are jointed to the outer ends of two lever-arms 17 by means of a rod 18. The inner ends of lever-arms 17 are rigidly joined together by a sleeve 17^a, which 80 surrounds a rod 19, the ends of the latter being supported by the brackets 10. The sleeve 17^a is provided with an inwardly-projecting locking-arm 20, the free end of which is provided with a roller 20^a to engage with a latching device 21 for the purpose of locking the circuit-breaker in closed position. The latching device 21 is provided with an arm 22 in 85 position to be engaged by a tripping projection 23 on a rod 24, which depends from the core 25 of a solenoid 26, the lower end of this rod being provided with weights 27, the number of which may be varied to suit desired 90 conditions.

The portion 12^b of the frame 12 is provided 100

with three arms, one of which is connected to a lug on the socket 13 by a coiled spring 28. The second is provided with a nose or projection 12^c, to be engaged by a lug 13^a on the socket 13, and thus limit the longitudinal movement of the arm 8, and the third is connected by a coiled spring 29 to the solenoid-supporting bracket 30 or other suitable stationary portion of the frame.

- 10 Loosely mounted upon the rod 19, so as to turn independently of the other mechanism under certain conditions, are two lever-arms 31, which are joined together below the other operating portions of the apparatus and provided with a handle 32 for closing the circuit-breaker. Each of these arms 31 projects upwardly and inwardly beyond the rod 19 and is provided with a laterally-projecting lug 33, so located and of such length as to engage 20 with the upper side of the adjacent lever-arm 17 to close the circuit-breaker. A rod 34 extends between the supporting-brackets 10 in position to serve as a stop for both the toggle-levers 16 17 and the operating-arms 31 and 25 handle 32, the lever-arms 16 being provided with projections 16^a to engage with this rod and the arms 31 being provided with similar projections 31^a. The free end of one of the operating-arms 31 is connected to some stationary portion of the apparatus, such as a projection from the base-plate or switch-board-panel, by a coiled spring 35.

The operation of the circuit-breaker is as follows: Assuming that the circuit-breaker 35 is closed, as indicated in the drawings, when the current passing through the flexible cable 9 to the movable and stationary contact-terminals exceeds the amount for which the circuit-breaker is adjusted by the weights 27 the 40 solenoid will overcome the pull of the said weights and will raise its core until the block or projection 23 engages the arm 22 of the latch and tilts the latter so as to release the arm 20. The spring 29 will immediately rock 45 the frame 12 on the rod 11, and the spring 28 will pull the arm 8 downwardly, so that the movable carbon terminal 7 will slide on the stationary terminal 5 without breaking contact, but will move the metal contact 6 away 50 from the end of the laminated contact 4, thus breaking the main circuit. A further action of the spring 29, in conjunction with gravity, will turn the frame 12 on the rod 11 and will throw the arm outwardly to the limit 55 of its movement, thus not only breaking the circuit, but separating the terminals a distance depending upon the length of the arm 8.

In closing the circuit-breaker the handle 32 will be moved inward to the position shown 60 in broken lines, the lugs 33 on the arms 31 bearing upon the toggle-lever arms 17, and thus forcing the parts toward the position in which they are shown in the drawings. When the carbon terminals 7 and 5 are first brought 65 into engagement, the position of the movable block 7 will be lower than the final position, as indicated in broken lines, and the lug 13^a

will be the same distance below the stop 12^c on the frame 12. In this position the metal contact-pieces 6 and 4 of the breaker will obviously be out of engagement. A further movement of the handle 32 will serve, by reason of the engagement of the two carbon blocks, to rock the arm 8 on its pivot 14 against the action of the spring 28 and will thus move 75 it longitudinally, so as to bring the movable main terminal 6 into engagement with the end of the laminated contact 4 and at the same time slide the movable carbon block 7 along the face of the stationary block 5, thereby insuring the keeping of the engaging faces clean and the making of a good contact between them.

While we have shown and described specific mechanism for carrying out our invention, it 85 is obvious that the details of construction may be varied by one skilled in the art, and we therefore do not desire to limit ourselves to the structural details shown and described.

We claim as our invention—

90 1. In an automatic electric-circuit breaker, the combination with a single stationary laminated contact-terminal and a single stationary carbon terminal, of a single movable terminal corresponding to each of said stationary terminals, a supporting-arm for said terminals having a flexible electrical circuit connection and pivoted to a hinged support, and means for actuating said support to swing the carbon contact-terminals into engagement 95 and thereafter move the supporting-arm longitudinally to bring the main terminals into engagement.

100 2. In an automatic electric-circuit breaker, the combination with a main and a shunt 105 stationary contact-terminal and two corresponding movable contact-terminals, of a supporting-arm for said movable terminals, a flexible conductor for connecting said movable terminals with a circuit, a hinged or pivoted frame to which said arm is pivoted, means for moving said arm and frame on the hinge of the latter to bring the shunt contact-terminals into engagement and for thereafter moving said arm longitudinally to bring 115 the main contact-terminals into engagement.

110 3. In an automatic electric-circuit breaker, the combination with a single main contact and a single shunt-contact in vertical alignment and connected to one circuit-terminal, 120 of a hinged arm having a main and a shunt contact at one end, a flexible connector extending through the arm to the other circuit-terminal and means for moving the arm in the arc of a circle to make and break the 125 shunt-circuit and longitudinally to make and break the main circuit.

125 4. In an automatic circuit-breaker, the combination with a carbon block and a laminated contact joined to one terminal of a circuit in vertical alignment, of an arm provided with a carbon block and a metal plate and having a double hinge connection with a supporting-base and toggle-lever and spring mechanism 130

for actuating said arm to move said block and plate respectively into and out of engagement with the stationary block and laminated contacts.

- 5 5. In an automatic electric-circuit breaker, the combination with a main and a shunt contact-terminal, of a hinged frame, a contact-bearing arm hinged to one side of said frame and having a spring connection with the other side, a toggle-lever for actuating said frame and a device moving independently of the

toggle-lever in one direction and engaging said lever to effect the closing of the circuit-breaker when moved in the opposite direction.

In testimony whereof we have hereunto ¹⁵ subscribed our names this 17th day of March, 1899.
